AUTOMATIC TIME AND VALVE CONTROLLING APPARATUS FOR YARN DYEING AND WASHING MACHINES

Application filed June 21, 1929. Serial No. 372,555.

This invention relates to improvements in an automatic time and valve controlling apparatus for yarn dyeing and washing machines.

5 At the present time it is the common practice to cause the dyeing solution, or liquid, to be forced through the yarn in one direction and then, after a definite interval of time, to cause the dyeing and washing liquids to be 10 forced through the yarn in the opposite direction. This is accomplished by winding the yarn on a spool formed with a hollow core having perforations therethrough. These spools with the wound yarn thereon are 15 mounted in a vat, or container, the bottom of which is formed with openings over which the open lower ends of the hollow cores of the yarn wound spools are placed. Below this bottom is a compartment which is termed a 20 false bottom that is in communication with pipe and pump connections for forcing the dyeing and washing fluid in opposite directions through the hollow cores and through the windings or layers of yarn in opposite 25 directions.

The invention further comprises means for accurately timing the flow in opposite directions of these two liquids through the spools.

At the present time it requires the attention 30 and services of at least two persons and a helper for operating each vat. The present invention is, therefore, designed to automatically control the dyeing and washing operation of several vats at the same time. This 35 is accomplished by means of electrical circuits and switches which will be fully described.

Referring to the drawings:

Fig. 1 is a side elevation partly in section 40 of one of the dyeing and washing vats, showing one of the spools and yarn thereon in section, also the pipe and pump connections;

Figs. 2 and 3 are detail sectional views of the control valves of the vats;

45 Fig. 4 is a plan view of the mechanism for operating the control valves and the electrical switch connections;

Fig. 5 is a plan view of the electrical timing mechanism for the dyeing and washing 50 operations;

Fig. 6 is a side view of Fig. 5; and Fig. 7 shows the wiring diagram of the electrical connections.

Referring to the drawings in detail: 1 designates the vat in which the spools 2 are 55 placed. These spools are formed with a hollow perforated core 3 having the opening 4. 5 is a rod which extends through the core for securing the spools 2 in place in the vat. This rod extends through the opening 6 in the floor 60 of the vat. 8 is a compartment between the floor 7 and lower floor or bottom 9. 10 are the supporting legs. A suitable cover 11 is secured to the top of the vat. 12 is the usual expansion tank which is connected to the top 65 of the vat with the pipes 13 and 14. 15 is a pipe leading from the bottom of the tank 12 to a circulating pump 16 which is connected by means of the pipe 17 to the bottom of the valve casing 18. Extending from the valve 70 casing is a pipe 19 that opens into the compartment 8. Another pipe 20 shown in Fig. 1 also opens into this compartment. This pipe is directly behind the pipe 19. Located on the top of the valve casing 18 is a plate 21 on 75 which is placed an electric motor 22 which operates the worm 23 that drives the worm gear or wheel 24 to which the link 25 is connected, at one end and to the valve arm 26, at its other end as shown in plan view in Fig. 80 4. This construction oscillates the two-way valve 27, as shown in Figs. 2 and 3. Attached to the liquid reversing valve 27 is an indicator rod 28 carrying a pointer 29 which indicates the position of the valve 27. 63 and 64 designate 85 the wires from the main line to the motor 22 in which is located the switch 62 for each vat. 32 designates an electric motor which is electrically connected to the line wires 33. This motor drives the two worms 34 and 35 90 which operate the worm gears 36 and 37. 38 and 39 are two sprocket chains which drive the worms 40 and 41 and these, in turn, rotate the worm gear wheels 42 and 43. The gear 42, as stated above, may be considered 95 as the "washing gear" and the gear 43 as the "dyeing gear". The speed of gear 43, may of course, be changed by changing the size of the sprocket wheel 37'. The gear 42 has secured thereto the switch operating member 100

44 which engages the arm 45 of the member 46 which slides in the supports 47, and 48. 49 is a coiled spring which is located in the slotted arm 48. This spring actuates a ball 50 which bears against the slidable member 46 to force it into locking engagement with the arm 48 when moved downward by 44. The slot in the arm 48 is indicated at 48'. The member 45 is notched at 46'. A coiled spring 51 normally draws the slidable member 46 upward to close the electric contacts 52 and open the electric contacts 53. The contacts 52 are electrically connected to the wire 54 and the line wire 33. The electric contacts 53 are connected to the wire 56 and line wire 33. Contacts 52 are electrically connected to the wire 58 and the pole 59 of the switch 62 and contacts 53 are connected to wire 60 and switch pole 61 of the double throw switch 62 which poles are electrically connected to the wires 63 and 64 to one each of the paired poles of the contacts 83 and 84. The other poles of said contact are connected to the electro-magnetic switch 98. The switch 98 is inserted in the line in order to start the motor 22, wired to 3 wire, 220 volts, from the 2 wire, 110 volt circuit used for the wiring to timing devices 42 and 43 and contacts 83 and 84.

30 The worm gear 43 operates to control the current in the wires 63 and 64 in the same manner as the worm gear 42. The gear 43 which is termed the dyeing gear is provided with switch operating devices 65 and 66 for 35 operating the slidable member 67 in the same way as the slidable member 46 is operated by switch operating devices 44 and 45' on the gear 42. The switch operating device 66 is adjustable while the device 65 is fixed. They 40 are so spaced on the worm 43 so as to time the dyeing operations for four minutes in flow, indicated as "In 4" and out seven minutes as indicated at "Out 7" and the radial lines 68 and 69 for example. The member 45 45 67 slides in the arms 70 and 71. A notch 72 and spring and ball 73 is employed to move the notch 72 into locking engagement with the slotted arm 71 in the same manner as described for the worm gear 42. 73' is a projection that is engaged by switch operating device 65 to move the slidable member 67 upward against the tension of the spring 67'. Contacts 74 are connected to the wire 75 and contacts 76 are connected to the wire 77 which 50 lead to the poles 78' and 79 respectively of the switch 62 which closes the circuit to the wires 63 and 64 when the switch 62 is thrown in the opposite direction to that shown to 55 close the circuit to the electromagnet or solenoid switch 98 which controls the valve operating motor 22. In Fig. 7 at the right hand end, the switch 62 is shown thrown to the right. This cuts in worm gear 43 for the 60 dyeing operations. This gear operates the

member 67 in the opposite direction from member 46 by the worm gear 42.

In Fig. 5 the cam member 66 is formed with a cam face 66' which engages the end of the arm 64' for moving the member 67 out of locking engagement with the arm 71, in a similar manner as that already described for the member 46, whereby the spring 67' will break the contacts at 74 and close them at 74''. Curved slots 66'' are provided for adjusting the member 66 and cam face 66' for varying the line of in and out flow of the dyeing liquid.

Located on the valve casing 18 (see Fig. 4) is a contact supporting member 80 and secured to the valve casing by means of the bracket arms 81 and 82. 83 and 84 are pairs of spring contact arms which normally close together. Wire 63 is connected to one of the contact arms of 84 and 64 is connected to one of the contact arms 83.

Slidably mounted in the extensions 89 of the bracket 80 is a member 90 having insulating material at its ends, as shown, for separating and insulating the spring contacts 83 and 84 from each other when it is moved in opposite direction by means of the adjustable stops 91 and 92 on the arms 93 and 94 of the oscillating valve 27. The plate 95 is secured to the valve 27 and is operated with the valve 27 by the arm 26 from the electric motor 22 by means of which the adjustable stops 91 and 92 engage in turn the projection 96 of the slidable member 90 for opening and closing the electric circuits at the contacts 83 and 84.

The operation may be described as follows: The electric motor 32 may be considered as operating continuously to drive the two worm gears 42 and 43. The switch 62 is in the position shown to close the circuits to the line wires 33 and contacts 52 which are about to be broken by the member 44 on the worm 42 at the beginning of, say a five minute period of the washing liquid flowing from the inside outward through the yarn wound spools 4 as indicated by the full line arrows in Fig. 1. It is understood that the reversing or oscillating valve 27 is in the correct position, as shown in Fig. 3, to cause the washing liquid to flow in the proper direction through the pipe 19 and return through pipe 20. At the termination of the "out flow" period of five minutes the member 44 moves the slidable member 46 downward, or towards the observer as shown in Fig. 5. This operation opens the electric contacts 52 and closes the electric contacts 53. The slidable member 46 is now locked in this position by means of the notch 46' in the slotted arm 48 by action of the spring 49 and ball 50. Current now flows by the wire 56, contacts 53, wire 60, switch 62, wire 63, contacts 84, wire 97 to the solenoid operated or magnetic switch 98, wire 99 to the line wires 33. This closes the circuit to

the valve operating motor 22, which, through the worm 23, wheel 24, link 25, and arm 26, rotates the valve 27 until the adjustable stop 91 engages the projection 96 and shifts the movable member 90, thereby opening contacts 83, stopping the motor 22 and closing the contacts 84. Valve 27 has thus been reversed and the liquid flows in the opposite direction through the yarn for five minutes. At the 10 end of that period the constantly rotating worm wheel 42 opens contact 53 and closes contact 52. This is caused by the cam face of member 45' on wheel 42 forcing back arm 64' of the bell crank 64², causing the face 64³ thereof to press against 46 and release it from engagement with slot 48', whereupon the spring 51 pulls 46 upward, breaking contact 53 and closing contact 52. This closes the circuit to motor 22, through wires 58 and 64, 15 contact 84, wire 97, and electro-magnetic switch 98, and the motor proceeds to revolve the valve 27 in the opposite direction until stop 92 engages the projection 96 and shifts member 90 and opens contact 84, thereby stopping the motor. At the same time contact 83 is closed, ready for the next operation. At the end of each five minute period, determined by worm wheel 42, the motor 22 is thus started, the valve 27 reversed, and the motor 20 thereupon stopped and the contacts 83 or 84 prepared for the next reversal. This operation of stopping and starting the motor 22 is continued as long as desired, or, until the switch 62 is opened. 101 is a brake device 25 for the motor 22. The magnetic brake 101 acts on the motor 22 to stop its revolutions immediately upon the breaking of the circuit to the motor, thereby preventing the gear 24 from overrunning, and thus maintaining the 30 link 25 and link 27 in proper position to hold the valve 26 in either of its operative positions.

When the switch 62 is thrown towards the 45 right hand the dyeing worm wheel 43 is put into operation in the same manner as the worm wheel 42 but with the adjustable timing members 65 and 66 so arranged as to cause the "in flow" for a period of, say four minutes and the "out flow" for seven minutes as 50 indicated by the radial lines 68 and 69.

It is to be understood that each one of the 55 vats 1 is controlled by a separate switch 62 and the inflow and outflow periods of the dyeing and washing liquid is automatically controlled by the worm wheels 42 and 43 which opens and closes the circuit to the motor 22 which, in turn automatically reverses the position of the valve 27, at the beginning and end of the in and out periods 60 of dyeing and washing and places the contacts for another operation.

It is of course obvious that any number of 65 vats may be simultaneously operated by throwing the switches 62 in the same position, or, any one or more may be in use.

The full and dotted arrows 100 and 101' in Fig. 1 indicate the flow and return of the washing and dyeing liquids.

It is to be understood by the term "washing", wherever used in the description, that 70 the generally accepted word for such operations is "scouring".

What I claim is:

1. In an apparatus of the kind described, in combination with a driven member, means 75 operated by the driven member for alternately opening and closing a pair of electric switches, a pump, a vat, pipe connections between the vat and the pump, a valve in the pipe connections, an electric motor for operating the valve, electric connections between the electric switches and the electric motor, and means operated by the motor for breaking the electric connections to the motor.

2. In an apparatus of the kind described, in combination with a driven member, means 80 operated by the driven member for alternately opening and closing a pair of electric switches, a pump, a vat, pipe connections between the vat and the pump, a valve in the pipe connections, an electric motor for operating the valve, electric connections between the electric switches and the electric motor, and means operated by the motor for breaking the electric connections to the motor, and 85 comprising a part secured to the valve, a movable member reciprocally operated by said part, and contacts for the purpose of stopping the motor by the movable member 90 for operating the contacts.

3. In a dyeing and washing apparatus in combination with a vat member having inlet and outlet pipe connections, a flow reversing valve in the connections, means for operating the valve, and means for timing the operations of the valve operating means. 105

4. A dyeing and washing apparatus having in combination with a vat member, pipe connections for circulating the liquid therethrough, an oscillating valve in the pipe connections for changing the direction of the flow of the liquid through the vat, an electric motor for operating the valve, an electromagnetic switch means for opening the circuit to the motor, switch devices operated by the motor for controlling the current to the said switch, and means for timing the flow of the liquid in opposite directions through the vat. 110

5. A washing and dyeing apparatus having in combination with a vat and pipe connections thereto, a reversible valve in the pipe connections for changing the direction of flow of the liquid, an electric motor, a worm and worm gear driven by the motor, crank and link connection between the valve and the worm gear, switch operated means connected to the valve for stopping the motor, a line wire, and timing means between the line wire and the electric motor switch operated 120 125 130

means for starting the motor and for pre-determining the length of time the said valve is in its different positions for changing the direction of flow either into or from the vat.

6. A dyeing and washing apparatus having in combination with a plurality of vats, pipe connections for each vat for directing the liquid into and from the vat, valves for changing the direction of flow of the liquid in the vats, a separate timing device for the dyeing and washing, means for operating each timing device, a power line, electric switches operable from each timing device, electric motors for operating the valves, electrical connections between the electric switches and the electric motors, and switch means operable by the electric motors for breaking the electrical connections and preparing for other connections to be made.

7. In combination, in a dyeing and washing machine, two timing devices, electric switches operated by the devices, an electric motor, a valve operated by the electric motor for controlling the flow of the dyeing and washing liquid to the vat in which the material to be dyed and washed is placed, switch operating means connected to the valve and operated from the same for automatically controlling the circuit to the motor, electrical connections between the timing devices and the motor and means in the connections for putting either the dyeing or washing timing gear into operation.

8. In a dyeing and washing apparatus, the combination with a vat and pipe connections therefor, a reversible valve in the pipe connections, an electric motor for operating the valve, electrical connections to the motor, a separate timing device for determining the time of the in or out flow of the two liquids through the vat, a switch in the connections for cutting in or out each timing device, and switch operated means in the connections which are controlled by the electric motor for breaking the current between the timing device and the motor.

9. In combination with a vat having pipe connections thereto and a reversing valve in the pipe connections, an electric motor for operating the valve, an electric circuit to the motor, means operated by motor and simultaneously with the valve for opening the electric circuit to the motor, and automatic means for timing the duration of flow of the liquid in the vat in one direction, and for timing it in an opposite direction.

10. In combination with a vat having pipe connections thereto and a reversing valve in the pipe connections, an electric motor for operating the valve, an electric circuit to the motor, means operated by motor and simultaneously with the valve for opening the electric circuit to the motor and assuming a position for the closing of another circuit to the motor, an automatic means for timing the

duration of the flow of the liquid in the vat in one direction, and for timing it in an opposite direction, said automatic means comprising a driven member, a pair of switches operated by and from the driven member, means 70 on the driven member for determining the period of time at which the pair of switches are operated, and electrical connections between the pair of switches and the circuit to the electric motor which operates the reversing valve.
